CARTRIDGE-TYPE LIPSTICK

Filed Sept. 15, 1948

UNITED STATES PATENT OFFICE

2,609,092

CARTRIDGE-TYPE LIPSTICK

Chester H. Braselton, New York, N. Y.

Application September 15, 1948, Serial No. 49,327

5 Claims. (Cl. 206—56)

1

This invention relates to lipsticks and other pomade or solid perfume applicators, and more particularly to those of the detachable type, such as shown in my co-pending application, Serial No. 699,026, filed September 24, 1946, now Patent No. 2,565,346, dated August 21, 1951, and relates more particularly to a design and construction for reducing the cost of manufacture of the types of cartridge applicators shown in my co-pending application above referred to.

This invention relates more particularly to improved means for establishing a driving relationship between the feeding mechanism of the cartridge and the casing or base adapted to receive the detachable cartridge when said cartridge is in place in the casing or base. It relates, generally, to means for establishing a frictional driving relationship for the feeding mechanism of the cartridge when the same is in place for use in the casing or base such that rotation of the wall of the cartridge with respect to the base when the cartridge is in place, will cause feeding of the pomade or lipstick material towards the applying end of the cartridge. By establishing this frictional driving connection as shown herein, it is not necessary to have the cartridge in any certain radial relationship when it is forced into position in the base, the establishment of the driving relationship being accomplished whenever the cartridge is pushed into position into the hollow casing of the base.

Another feature of this invention is the construction wherein the wall of the cartridge, preferably made of metal of tubular formation, is forced inwardly by swaging or rolling to form an integrally projecting spline in the wall of the tube from which the cartridge is made. This spline or longitudinal indentation does not extend the whole length to the extreme ends of the cartridge tube, but leaves a portion at one end circular at the inside diameter, wherein may be mounted for rotative, but non-longitudinal movement with respect thereto, a closure for closing that end of the cartridge and serving to rigidly support a feeding screw axially in the cartridge. The fastening of the circular end of the cartridge with the closure mounted partially therein is accomplished by having a peripheral groove located in the periphery of a smaller diameter of the closure which is adapted to fit within the circular end of the cartridge. The cartridge is placed over this small diameter of the closure and is then spun inwardly to establish non-longitudinally movable, but rotative connection between the closure and the adjacent end of the cartridge. A plunger is threadedly mounted on the longi-

2

tudinal screw and has a groove or notch in its periphery adapted to engage the inwardly projecting spline of the cartridge to establish non-rotative connection between the plunger and the spline of the cartridge. The closure for the end of the cartridge has another diameter greater than the inside diameter of the cartridge, below where the cartridge engages the closure, and this enlarged diameter of the closure is sufficiently large to fit loosely in the inside diameter of a hollow casing which forms, or is connected, with the base of the casing. The enlarged diameter of the closure has a peripheral groove adapted to receive a frictional driving means, the tension of which holds it in place in the groove but which extends slightly beyond the periphery of the larger diameter of the closure so as to establish a frictional driving connection with the inside wall of the hollow casing when the cartridge is assembled.

In the drawings which accompany and form a part of this application,

Fig. 1 is a view of my lipstick or other applicator with the cap or closure therefor in place thereon.

Fig. 2 is a longitudinal, sectional view taken on line 2—2 of Fig. 1, looking in the direction of the arrows.

Fig. 3 is a perspective view of the device of Figs. 1 and 2, with the cap removed.

Fig. 4 is a cross-sectional view of Fig. 2, taken on line 4—4, looking in the direction of the arrows.

Fig. 5 is a cross-sectional view of Fig. 2, taken on line 5—5, looking in the direction of the arrows, and

Fig. 6 illustrates the relationship of the parts when the inside open edge of the cartridge receiving casing is bevelled, tending to serve as a wedge to further aid in wedging the circular spring, carried by the closure for the cartridge, inwardly during the beginning of insertion of the cartridge in its hollow casing.

In the drawings, 1 represents a shouldered enlargement of the hollow casing adapted to detachably receive a lipstick or pomade-containing cartridge 2. 3 represents the cap or closure adapted to cover the cartridge in the upper end of the hollow casing when in place thereon, and serve as a protective cover. The shouldered portion 1 of the hollow casing 4 serves as an abutment for the cap and also as a grip for holding the hollow casing. This casing 4 has an external abutment 5 to limit the downward movement of the cap when placed thereon, said cap being held on the casing by frictional engagement with the

periphery 6 of the hollow casing. The casing 4 is further reduced in diameter at 7 to relieve this area against scratching when the cap is put on or taken off. Casing 4 is hollow on the inside, having an inside diameter 8 slightly bevelled at 9 at its open end on the inside. The hollow casing is closed by a closure 10 at its bottom end, either integral with or attached thereto.

The cartridge 2 of my invention is constructed from a tube of circular inside diameter with the exception that at one portion of the periphery, preferably on the longer side, the walls of the tube is forced in by rolling or swaging so as to form an inwardly projecting, relatively unnoticeable spline 11, this extending from point 12, near one end, to the point 13 near the other end, but not extending throughout the whole length of the cartridge tube. The purpose of this spline is to establish non-rotative connection between the cartridge 2 and plunger 14, which has a notch 15 adapted to fit over spline so that the plunger 14 may move longitudinally with respect to the cartridge 2, but not be rotated with respect thereto.

One end of the cartridge 2 is closed by closure 16, having a portion 17 of a diameter such as to fit the inside circular wall of that end of the cartridge tube. The closure 16 has another portion 18 of larger diameter adapted to movably fit the inside diameter of the hollow casing. This portion of larger diameter and the portion of small diameter adapted to fit inside of the cartridge tube, are separated by a peripheral groove 16a in the closure, the smallest diameter of which is less than the outside diameter 17, and provides spaced into which the lower end of the cartridge 2 may be spun into to form a rotative, but non-longitudinally movable relationship between the cartridge 2 and the closure 16. The closure 16 has a screw 19 rigidly fastened thereto, either by peaning, force-fitting, soldering, or otherwise, which closure supports this screw axially of the cartridge 2. The plunger 14, above referred to, has a central opening threaded to fit the screw 19 so that these two elements are threadedly connected. Rotation of the closure 16, with respect to the cartridge 2, will cause the plunger 14 to move only longitudinally of the cartridge 2, being prevented from rotation with respect thereto by the spline 11 working in notch 15. In this way the lipstick or other pomade material which fills the space between the plunger 14 and the applying end of the cartridge is fed towards the applying end when the closure 16 is rotated in one direction with respect to the cartridge 2. In this way lipstick or other pomade material may be kept supplied to the applying end of the cartridge by rotating the closure 16 with respect to the cartridge 2.

In order to establish a relationship whereby the cartridge is held in place in the hollow casing 4, and whereby the closure 16 may be caused to be rotated with respect to the cartridge 2 when the hollow casing 4 is rotated with respect to the cartridge 2, I provide on the portion 18 of the closure 16 of a diameter larger than the diameter 17, a peripheral groove 20 therein, in which is mounted a spring 21 of such tension and diameter as to be held in the groove 20 by its tension, yet portions thereof allowed to yield inwardly when the closure and cartridge are pushed into the open end of the hollow casing 4. The spring 21 does not project sufficiently beyond the large-diameter 18 of the closure, but that the projecting portions thereof will always be wedged

inwardly by the open end of the hollow casing when the cartridge is forced into place. To make sure of this inward wedging of the spring, I, in some cases, provide a slightly internal bevel 9 in the open end of the hollow casing which further tends to wedge the spring inwardly at the beginning of the insertion of the cartridge in place. The diameter of the spring 21, when in its peripheral groove 20, and the depth of the groove therein, is such that less than half of the diameter of portions of the spring is all that projects beyond the internal diameter of the hollow casing 4, the spring stock being of sufficient diameter and strength as to yield inwardly as the spring is wedged inwardly due to insertion of the cartridge in the hollow casing. I prefer that the spring, when in place and acting freely, does not project at any point more than half of the cross sectional diameter of the stock from which it is formed, beyond the extreme periphery 18 of the closure, and better operation is found when the clearances are such that the spring does not project even this much beyond the large diameter 18 of the closure. The spring preferably yields just enough to allow the insertion of the cartridge readily, it being of sufficient strength as to establish a firm, yielding, driving relationship between the closure 18 and the inside of the hollow casing, the spring serving, by this frictional connection, to not only retard or prevent rotation of the closure with respect to the hollow casing, but also to hold the cartridge in place longitudinally during the use of the device, yet still permitting ready removal of the cartridge by pulling the same longitudinally whenever it is desired to disconnect the same from the hollow casing. The spring ring 21 need not be, and indeed preferably is not, made with great care to obtain exact circularity or flatness, as it is its departure from true circularity or flatness that insures its obtaining a driving grip on the closure 16 for the cartridge sleeve 2, as well as the wall 4 of the base 1, when the cartridge is entered into the base in any position of relative rotation of the two, as shown in Fig. 2.

In Fig. 6 I have shown, by enlarged view, the action of the wedging surface 9 on the hollow casing aiding to wedge portions of the circular spring 21 inwardly at the moment of beginning of insertion of the cartridge in the hollow casing. While this is not always necessary it is useful in helping to prevent any jamming of the spring between the large diameter portion 18 of the closure 16 and the inside of the hollow casing 4 in case too loose a fit should otherwise exist between this closure and the hollow casing. When these parts are made with the proper tolerances and dimensions, however, the internal bevel of the open end of the hollow casing may be eliminated, if desired, although in certain relationships of the cross-sections this beveling of the interior of the hollow casing may be an advantage.

I have shown an irregular shaped open end of the applicator 2, such as shown in my allowed application, Serial No. 699,025, filed September 24, 1946, as I find this a very beneficial shape for the end of the applicator for lipsticks, and highly desirable, to always provide a ridge of free lipstick material across the diameter of the cartridge. This, of course, is not necessary for other forms of pomade or solid perfumes, in which case I generally have the applicator end of the cartridge shaped straight across. For some other forms of applicators for the cartridges, the car-

tridges, however, may have to be shaped for the particular uses desired.

Having described my invention, what I claim is:

1. In a cosmetic applicator of the removable cartridge type, in combination, a hollow base adapted to detachably receive a cover for the applicator; a detachable cartridge comprising a sleeve open at its upper end; said cartridge having a closure mounted at the lower end of its sleeve in rotatable but non-longitudinally movable relation to its sleeve; said closure formed to enter said base in any rotated position relative to said base; said closure comprising means establishing, in any such position of entry, a frictional retaining and driving connection between said closure and said base; said cartridge sleeve, in said entered position, extending beyond said base; and feeding mechanism inside the cartridge operable by relative rotation of said sleeve and base.

2. In a cosmetic applicator of the removable cartridge type, in combination, a hollow base adapted to detachably receive a cover for the applicator; a detachable cartridge comprising a sleeve open at its upper end; said cartridge having a closure mounted at the lower end of its sleeve in rotatable but non-longitudinally movable relation to said sleeve; said closure being generally cylindrical and of a size to enter said base in any rotated position relative to said base; said closure comprising a peripheral groove therein and a resilient frictioning element in said groove establishing, in any such position of entry, a frictional retaining and driving connection between said closure and said base; said cartridge sleeve, in said entered position, extending beyond said base; and feeding mechanism inside the cartridge operable by relative rotation of said sleeve and base.

3. In a cosmetic applicator of the removable cartridge type, in combination, a hollow base adapted to detachably receive a cover for the applicator; a detachable cartridge comprising a sleeve open at its upper end; said cartridge having a closure mounted at the lower end of its sleeve in rotatable but non-longitudinally movable relation to said sleeve; said closure being generally cylindrical and of a size to enter said base in any rotated position relative to said base; said closure comprising a peripheral groove therein and a spring mounted in said peripheral groove establishing, in any such position of entry, a frictional retaining and driving connection be-

tween said closure and said base; said cartridge sleeve, in said entered position, extending beyond said base; and feeding mechanism inside the cartridge operable by relative rotation of said sleeve and base.

4. In a cosmetic applicator of the removable cartridge type, in combination, a hollow base adapted to detachably receive a cover for the applicator; a detachable cartridge comprising a sleeve open at its upper end; said cartridge having a closure mounted at the lower end of its sleeve in rotatable but non-longitudinally movable relation to said sleeve; said closure being generally cylindrical and of a size to enter said base in any rotated position relative to said base; said closure comprising a peripheral groove therein and a spring-ring mounted in said peripheral groove establishing, in any such position of entry, a frictional retaining and driving connection between said closure and said base; said cartridge sleeve, in said entered position, extending beyond said base; and feeding mechanism inside the cartridge operable by relative rotation of said sleeve and base.

5. A tubular cosmetic applicator cartridge comprising a sleeve open at its upper end, a plunger within the sleeve and movable longitudinally thereof, said cartridge comprising a closure mounted in the lower end of said sleeve in rotatable but non-longitudinally movable relation to said sleeve and projecting therefrom, said closure having a peripheral groove, a spring ring mounted in said groove for establishing a frictional connection of said closure to a casing member, and means within the cartridge for moving the plunger longitudinally therein in response to relative rotation of said sleeve and closure.
